SHOE HEATER

Filed Aug. 19, 1922

2 Sheets-Sheet 2

Patented May 29, 1928.

UNITED STATES PATENT OFFICE.

WILLIAM H. BAYNARD, OF QUINCY, MASSACHUSETTS, ASSIGNOR TO HARRY H. BECKWITH, OF BROOKLINE, MASSACHUSETTS.

SHOE HEATER.

Application filed August 19, 1922. Serial No. 582,942.

This invention relates to shoe heaters having been more particularly designed to facilitate the incorporation in the shoe of a counter made of material stiff and hard at ordinary atmospheric temperature but which becomes soft and pliable when subjected to heat or heat and moisture such as those made of fibrous material impregnated with asphaltic or suitable thermoplastic compounds. 10 Such counters when assembled between the upper and lining of the shoe are "half molded" or bent laterally to conform roughly to the sides and heel end of the lasts. It is then necessary to form the counter closely to the last and to bend the lower edge or heel seat flange which, as assembled, projects below the lower edge of the last, over against the bottom face of the insole as the upper and lining are drawn thereover and made fast 20 thereto in the lasting operation.

The present invention, therefore, provides a construction whereby the assembled shoe may be supported sole downward in position to have directed against the lower face of the heel adjacent its margin, currents of hot vapor or steam. The steam or vapor then acts very directly on the edge or flange of the counter which projects below the last and which is to be bent against the lower 25 face of the insole and softens it so that it may be readily bent to the required shape. The counter above this edge is acted on to a less extent by the steam or vapor but sufficiently to cause it to soften to permit it to be conformed to the shape of the last as the 30 upper and lining are drawn thereover in the lasting operation. By the use of moist heat the leather of the upper acted on thereby is put in temper and is rendered more workable during the lasting operation.

For a more complete understanding of this invention, together with further objects and advantageous details and combinations of parts, reference may be had to the accompanying drawings illustrating an embodiment thereof in which.

Figure 1 is an end elevation partly broken away of the heel heater showing in dotted lines the position of an assembled shoe thereon.

Figure 2 is a fragmentary detail showing a connection from this heater to a toe heater by which the heel heater may be supported.

Figure 3 is a top plan of the heater.

Figure 4 is a detail section on line 4—4 of

Figure 1 showing the manner of mounting a heating element.

Figure 5 is a plan of another form of heating element.

Figure 6 is a detail in perspective.

Referring to Figures 1 and 3 the heater comprises a platform 1 having a marginal upstanding flange 2 extending about three sides thereof and forming a partial enclosure to receive the heel end of an assembled shoe. The last 3 of the assembled shoe should be supported somewhat above the upper face of the platform 1 in order to permit the upper and counter to project therebelow. This is clearly illustrated in Figure 1 in which the counter is indicated at 4, the upper at 5 and the lining at 6, the counter being placed between the upper and lining in the usual manner. For supporting the heel in this position, a rest or support with which the last or lower face of the insole may be engaged is indicated at 7 and as shown comprises a cap bolt which is threaded through the platform 1, its head serving as the desired support for the last. While a platform 1 may be made individually to support a single assembled shoe, it may be desirable in many cases to form it in a series with other similar platforms in a single unit to receive simultaneously a plurality of assembled shoes to be treated, as is indicated in Figure 3. As therein shown the platforms 1 between the flanges 2 of the several units are connected by means of webs 8 which may, if desired, be substantially continuations of the platforms 1.

The platforms 1 form the upper face of a receptacle having downwardly and inwardly inclined walls 10, 11 which may be formed integral therewith and at their lower ends are shaped to form a substantially cylindrical passage 12 extending laterally of the platforms 1 and longitudinally of the heater beneath the entire series. This cylindrical passage 12 is formed to receive a heating unit, one form of which is shown in detail in Figure 4. Referring to this figure, at 15 is shown a tube which passes through openings 16 in end walls 17, uniting the walls 10 and 11 and extends through the cylindrical portion 12. Each end of the tube 15 has inserted therein a plug 18 having a central bore 19 and a flange 20 at one end. This flange 20 is arranged to be seated

against the outer face of the wall 17 and the plug is expanded into clamping relation with the tube 16 by means of a tapered pin 21 which is driven into a tapered opening 22 intermediate the end of a slot 23 extending from the bore 19 to the periphery of the plug.

Positioned within the bore 19 is shown an electric heating unit 24 having radiating fins 25 thereon which extend toward the walls of the tube 15. This unit 24 is provided with end flanges 27 overlying the ends of the plugs so that when the plugs are fixed in position the unit is also fixed within the tube 15. At one end of the unit is fixed an electrical conductor 29 and at the other end is fixed a similar conductor 30. For convenience in making electrical connections the conductor 30 may be passed through a pipe 31 extending between the end walls 17 of the heater beneath the cylindrical portion 12. This cylindrical portion has a passage 35 extending from its lower portion out through the rear wall 11 where it connects with a pipe fitting 36 to which may be attached a flexible pipe 37 by which water may be introduced into the portion 12 surrounding the tube 15 in position to be heated by the heating unit. As shown the pipe fitting 36 is clamped against the heater by means of a dog 45 made fast by a thumb screw 46 to one face of the support. The steam produced passes upwardly into the space directly beneath the platforms and is permitted to pass through these platforms and into contact with the bottom face of the shoe in position to act quite directly on the portions of the counter, lining and upper, extending below the bottom face of the insole so that they may be heated and the counter softened to permit it to be drawn about the under face of the insole and made fast thereto in the subsequent lasting operation. For the purpose of directing the vapor in the proper manner against the shoe curved slots or perforations 40 through the platforms 1 are shown between the last support 7 and the marginal flange 2.

The mechanism thus described may be supported in any suitable manner, but as shown is intended to be coupled with a toe heater of any suitable description. As various sizes of shoes are worked upon it is desirable that the distance between the toe and heel heaters shall be adjustable.

One manner of supporting the heel heater from the toe heater with capability of such adjustment is shown in Figures 1, 2, and 3 in which a pair of rack bars 50 made fast to the base portion of the heel heater extend beneath a portion 51 (see Figure 2) of the toe heater and over a supporting rod 52 journaled in one end of a hanger 53 suspended from the portion 51 of the toe heater by means of a hook 54 and a link 55. Where

the rack bars pass over the rod 52 this rod is preferably cut away to form teeth intermeshing with the rack teeth by which construction by rotating the bar 52 the racks 50 may be moved in and out to position the heel heater at the required various distances from the toe heater, the heel heater being suspended from the toe heater by means of the construction above described. It will be noted that the heel heating means is independent of the toe heating means.

The conductors 29 and 30 above referred to may be brought together within a suitable conduit 60, as shown in Figure 1, and may pass to the toe heater and be connected to the leading in wires for the latter heater if it is so desired.

Instead of the heating element fixed within the tube 15 the heating unit shown in Figure 5 may be employed which comprises a heating element 65 formed U shape and made fast at opposite ends in a plug 66 which may be threaded in an opening in one of the end walls 17, the other end wall being unperforated when this form of heating unit is employed. The electric conductors are connected to the ends of this member 65 and since they are both at the same end of the unit there is no necessity for the return pipe 31 as in the form shown in Figure 3.

Having thus described an embodiment of this invention, it should be evident that many changes and modifications might be made therein without departing from its spirit or scope as defined by the appended claims.

I claim:

1. In combination, a toe heater, hangers carried by said toe heater, a support carried by said hangers, bars slidable on said support, a heel heater carried by said bars, and means for sliding said bars to adjustably space said heaters.

2. In combination, a toe heater, hangers carried by said toe heater, a support carried by said hangers, rack bars slidable on said support, a shaft journaled in said supports and having pinion portions meshing with the teeth of said rack bars, and a heel heater carried by said bars, whereby turning said shaft adjustably spaces said heaters.

3. A device of the class described comprising a platform, a support extending above the top of said platform on which the heel portion of the sole of an assembled shoe may be supported, and means for conducting vapor through openings in said platform against the lower face of the shoe.

4. A device of the class described comprising a platform, a marginal upstanding flange thereon shaped to partially enclose the heel portion of an assembled shoe, a support extending upwardly from said platform and spaced from said flange, said platform being perforated between said support and

flange, and a vapor generator beneath said platform and communicating with said perforations.

5. A device of the class described comprising a casing having a substantially cylindrical lower portion extending longitudinally thereof, a top for said casing comprising a plurality of platforms on which may rest the heels of assembled shoes, said platforms having openings therethrough in position to direct vapor from said casing against the shoes, a heating element extending axially of said cylindrical portion, and means for introducing material to be vaporized into said cylindrical portion about said element.
- 10

6. A device of the class described comprising a casing having a substantially cylindrical lower portion extending longitudinally thereof, a top for said casing comprising a plurality of perforated platforms, a marginal upstanding flange about each platform shaped to partially enclose the heel end of an assembled shoe, a support on each platform for receiving the shoe and spacing the shoe above said platform, a heater longitudinally arranged in said cylindrical portion, and a pipe communicating with said cylindrical portion.
- 15

7. A device of the class described comprising a platform, an upwardly extending flange partially surrounding a portion of said platform and shaped to partially enclose the heel portion of an assembled shoe, a support for engaging the heel portion of the sole of the shoe extending upwardly from said platform and spaced from said flange to permit the marginal portion of the shoe upper extending below the shoe sole to project into said space, said platform having openings therein between said support and flange, and means for directing vapor through said openings to contact with the heel portion of the shoe.
- 20

8. A device of the class described comprising

ing a platform, an upwardly extending flange partially surrounding a portion of said platform and shaped to partially enclose the heel portion of an assembled shoe, a support for engaging the heel portion of the sole of the shoe extending upwardly from said platform and spaced from said flange to permit the marginal portion of the shoe upper extending below the shoe sole to project into said space, said platform having openings therein between said support and flange, and forming the upper face of a water receptacle, and a heating unit in said receptacle for vaporizing the water, the vapor reaching the shoe through said openings.

25

9. A device of the class described comprising a support for the heel end of an assembled shoe constructed to enclose the heel seat portion of a counter stiffener and upper materials, said support having openings therethrough through which a treating agent may pass into contact with the inner face of the heel seat portion of the stiffener.

30

10. A device of the class described comprising a support for the heel end of an assembled shoe constructed to enclose the heel seat portion of a counter stiffener and upper materials, said support forming the upper face of a receptacle and having openings therethrough through which a heated vapor may pass into contact with said heel seat portion.

35

11. A device of the class described comprising a receptacle having a platform closing its upper end, said platform having a series of spaced flanges each shaped to partially enclose the heel end of an assembled shoe and provided with openings within the lines of said flanges through which a treating agent may pass from said receptacle into contact with the partially enclosed shoe.

40

In testimony whereof I have affixed my signature.

WILLIAM H. BAYNARD.
